UNITED STATES PATENT OFFICE.

THOMAS JACKSON, OF LONDON, ENGLAND, ASSIGNOR TO GLENDORA BESSIE RAMSAY,
OF FOLKESTONE, ENGLAND.

GOVERNING DEVICE.

Application filed August 24, 1923, Serial No. 659,077, and in Great Britain August 31, 1922.

This invention relates to improvements in governing devices in which the inertia of a reciprocated mass is employed and has for its object the provision of means whereby 5 increased efficiency and smoother controlling function is obtained as compared with known devices.

The invention consists in an arrangement of parts for governing purposes comprising 10 a pivoted lever for oscillation by the apparatus the speed of which is to be controlled, a pivoted lever carrying a mass adapted to be oscillated by the first named lever through two oppositely disposed yielding resistances, a bifurcated pivoted lever 15 having two abutments said bifurcated lever being adapted to be angularly displaced when the lever carrying the mass contacts with either of the abutments, a valve device 20 mechanically associated with and operable by the bifurcated lever adapted to permit passage of motive fluid under pressure when the bifurcated lever is angularly displaced, a fluid pressure operated control device connected directly or indirectly to the delivery 25 from the valve device said control device acting against an increasing yielding resistance and being adapted to return to its initial position on interruption of the supply of fluid pressure, connecting means between the control device and that which 30 directly controls the speed of that which is to be controlled and a source of motive fluid.

Referring to the drawings, which form 35 part of this specification,—

Figure 1 is a front elevation of a governing device constructed in accordance with this invention.

Figure 2 is a fragmentary plan view of 40 Fig. 1.

Fig. 3 is an enlarged section through the valve device operated by the momentum of the reciprocating mass for governing.

Figure 4 is an enlarged section of one 45 form of the valve device associated with the fluid pressure operated control cylinder.

The device illustrated in the drawings is arranged to employ compressed air or steam under unvarying pressure as motive fluid, 50 the pivoted lever *a*, which for constructional purposes is bifurcated, is adapted to be reciprocated by the rod *b* connected to a moving part of that which is to be controlled,

a second pivoted lever *c* carrying a mass *d* being mechanically associated with the lever *a* by means of two adjustable springs *e* *e* or the like, so that when the lever *a* is oscillated it in turn oscillates the lever *c*. 55

It will be seen that owing to the yielding nature of the connection between the levers *a* and *c* when the lever *a* is oscillated at a certain speed the lever *c* will substantially follow its oscillations but when the speed of the lever *a* is increased beyond a certain speed the lever *c* will have a greater amplitude of motion due to the inertia of the mass *d*, the critical speed being entirely dependent upon the strength of the springs *e* *e* or the like employed or the position of the mass *d* on the lever *c*. 60

The lever *c* during its oscillations operates between stops *f* and *g* mounted on a pivoted bifurcated lever *h*, the distance between the stops *f* and *g* when adjusted for a specific speed being sufficient to permit of 70 the normal oscillation at that speed of the lever *c* without contact therewith, so that while the oscillation of the lever *c* is normal no displacement of the lever *h* takes place; when however, the oscillation of the lever *c* becomes abnormal due to increase of speed 75 above that predetermined, the stops *f* and *g* on lever *h* are contacted by the lever *c* and the lever *h* is angularly displaced.

The lever *h* is mounted on the part of 80 the stem *i* which protrudes through the cover of the valve device *k* which includes a valve seat *l*, a ball valve *m* and ball engaging member *n* which is carried and operated by the part of the stem *i* within the device *k*. 85

The ball engaging member *n* as illustrated is provided with four arms each of which can be employed to operate the valve *m* as required.

When the lever *h* is in mid position one 90 of the arms of the ball engaging member *n* is also in mid position with the result that the ball valve *m* engages with its seat *l* thus preventing passage of motive fluid through the device *k*, but when the lever *h* is displaced from the mid position one or other of the projections *n'* of the member *n* will engage with the ball *m* and displace it from its seat *l* thus permitting motive fluid to 100 flow through the device *k*. 105

The exit connection of the device *k* is con-

nected to a power control cylinder o containing a piston p so that when the motive fluid at constant pressure passes through the device k the piston p is displaced against an increasing yielding resistance such as the spring p' .

To control the distance through which the piston p is displaced by the motive fluid a power operated valve acting against an adjustable yielding resistance is inserted in the operative end of the cylinder o and is adapted to allow any excess beyond a predetermined pressure in the cylinder o to escape.

As illustrated the power operated valve comprises a plunger q having portways r therein said portways r registering with portways s in the body t during operation of the device, a spring u and finger operable adjusting means v being provided to introduce the requisite yielding resistance.

In operation motive fluid is supplied to the tube at the extreme right hand side of Figures 1 and 4, the pressure of this motive fluid is always the same. If the spring u were not in place then the piston q would pass to the extreme left hand end of its travel. The presence of the spring u however prevents this and the spring u is so adjusted that when the motive fluid is applied the piston q moves to the left only such amount as partially will cut off the passage of fluid through the portways r and s a small escape of motive fluid always freely taking place.

When the pressure of the motive fluid has been settled for any given plant then the spring u is adjusted by the finger operable adjusting means v so that the portway r slightly overlaps the portway s when the motive fluid exerts pressure on the piston q . After the spring u has been so adjusted the pressure of the motive fluid must not be varied.

To ensure that the piston q shall move smartly as soon as the motive fluid is admitted, the axial portway which establishes connection between the transverse portway r and the operative end of the piston q is of comparatively small diameter. In a piston one inch in diameter, the diameter of the axial portway may be one sixteenth of one inch in which case the area of the axial portway is only one two hundred and fifty sixth part of the area of the piston q .

When motive fluid is admitted under working conditions the piston q moves to the left until the force exerted by compressing the spring u is equal to the force exerted by the motive fluid on the end of the piston q ; the piston p is also raised by the motive fluid until the force exerted by compressing the spring p' is equal to the force exerted by the motive fluid on the piston p .

The force available for operating the piston p can be adjusted by varying the amount

of leakage which is permitted to take place through the portways r and s and thus the travel of the piston p on operation can be controlled within wide limits by adjusting the spring u .

The arrangement outlined above is double-acting in operation inasmuch as if the velocity of the oscillations of the lever a in either direction is in excess of that predetermined by adjusting the spring e displacement of the lever h causes movement of the piston p within the power cylinder o .

With such arrangements it is obvious that if the rod w of the piston p is connected to the control of that which is to be controlled when any excess of speed beyond that predetermined takes place due to disturbance of load factor automatic control instantly ensues and all racing is prevented.

In some cases when an abnormal increase of speed takes place or that which is to be controlled for some reason is temporarily unresponsive to normal governing action a trip device may be provided adapted to prevent return movement of the piston p after displacement of predetermined amount.

In Fig. 1 the upper part of the rod w is provided with a screw thread with which a collar x is operatively engaged a pivoted detent y being provided to engage with the collar x and maintain it in position if the travel of the rod w is sufficiently excessive. To enable the collar x and the detent y to be disengaged a pivoted lever z is provided.

I claim:

1. An improved governing device having in combination a pivoted lever continuously oscillated by the apparatus the speed of which is to be controlled, a pivoted lever rigidly carrying a mass adapted to be oscillated by the first named lever through two oppositely disposed yielding resistances, a bifurcated pivoted lever having two abutments said bifurcated lever being adapted to be angularly displaced when the lever carrying the mass contacts with either of the abutments, a source of motive fluid under constant pressure, a valve device mechanically associated with and operable by the bifurcated lever adapted to permit passage of motive fluid under pressure when the bifurcated lever is angularly displaced, a fluid pressure operated control device connected to the delivery from the valve device said control device acting against an increasing yielding resistance and returning to its initial position on interruption of the supply of fluid pressure.

2. In an improved governing device as claimed in claim 1 the arrangement of a fluid pressure operated valve device comprising a cylinder, a piston in said cylinder, a spring for maintaining the piston in position against the fluid pressure, a transverse portway in said piston, a portway for con-

ducting motive fluid under pressure to said transverse portway from said cylinder, ports in said cylinder so located that communication can be effected between said ports and 5 the transverse portway in said piston to allow motive fluid to escape, an escape branch in the cylinder communicating with

said ports, a branch for admitting motive fluid under pressure into said cylinder and a branch for conducting motive fluid to a ¹⁰ fluid pressure operated control device.

In testimony whereof I have signed my name to this specification.

THOMAS JACKSON.
